UNITED STATES PATENT OFFICE.

LEVI CLIFTON SPARKS AND AUGUST WILLIAM LOUIS HARTBAUER, OF ST. LOUIS, MISSOURI, ASSIGNEES TO AMERICAN CAR AND FOUNDRY COMPANY, OF ST. LOUIS, MISSOURI, A CORPORATION OF NEW JERSEY.

REMOVABLE DECK-SCREEN FOR STEEL PASSENGER-CARS.

1,097,948.

Specification of Letters Patent.

Patented May 26, 1914.

Application filed September 30, 1911. Serial No. 652,176.

To all whom it may concern:

Be it known that we, LEVI CLIFTON SPARKS and AUGUST WILLIAM L. HARTBAUER, residing at St. Louis, Missouri, and being 5 citizens of the United States, have invented certain new and useful Improvements in Removable Deck-Screens for Steel Passenger-Cars, of which the following is a full, clear, and exact description, such as will enable 10 others skilled in the art to which it appertains to make and to use the same, reference being had to the accompanying drawings, which illustrate the preferred form of the invention, though it is to be understood that 15 the invention is not limited to the exact details of construction shown and described, as it is obvious that various modifications thereof will occur to persons skilled in the art.

20 In said drawings: Figure 1 is a side elevational view of a portion of the window deck of a car constructed in accordance with this invention. Fig. 2 is a transverse vertical sectional view through a deck window 25 and adjacent parts constructed in accordance with this invention said section being taken on line 2—2 of Fig. 1. Fig. 3 is a horizontal sectional view taken on the plane of line 3—3 of Fig. 2. Fig. 4 is a fragmentary vertical sectional view similar to the upper portion of Fig. 2 and illustrating a modification. Fig. 5 is a vertical sectional view similar to Fig. 2 illustrating a further modification. Fig. 6 is a horizontal sectional 30 view taken on the plane of line 6—6 of Fig. 5. Figs. 7 and 8 are, respectively, enlarged fragmentary details of the upper inner portion of the window-pan shown in Fig. 5 and the lower portion of the window-deck-frame 35 of the same figure.

40 Screen frames as heretofore manufactured, for cars to which this invention is applicable, have been riveted securely into place against the metallic roof framing and window pan of the car, the only readily removable part being the small bead by which the wire mesh itself is secured. Such a structure affords inaccessible corners and other portions from which rust cannot 45 easily be removed. This condition constitutes a serious defect in the construction of the cars and shortens the lives thereof. The removal of the wire mesh for repairs, cleaning or for other purposes, from frames

rigidly held, constitutes, of itself, a tedious 55 problem which is not undertaken by workmen except in extreme necessity.

The object of this invention is to avoid the deficiencies found in the structure referred to and it provides a screen frame 60 constructed independently of the car, to which the mesh may be applied, removed or cleaned while the frame is detached, and on a workman's table if desired.

It provides further that the frame may 65 be easily attached or removed from its position in the window pan for removing or adjusting the mesh or for giving access to the window pan for refinishing the pan or surrounding parts of the car structure. 70

Referring to the drawings by numerals, 1 indicates one of the deck windows, 2 the outwardly flaring rectangular window pan which surrounds the window and forms a hood between the window and the screen 75 spaced therefrom. The opposite vertical sides of the pan 2 lap the forward face of and are fixed to the vertical portion of the roof carlines 3 arranged between the windows, said lapping portions being connected 80 to said carlines by suitable rivets as at 4, and said lapping portions of adjacent window pans being covered by intermediate finishing plates as 5 secured in place by the rivets 4. The outer edge of each of the four 85 sides of the pan 2 are depressed or shouldered to form a recess 6, adapted to surround and receive the screen frame 7.

The water table or eaves molding 8, extending longitudinally of the car, depends, 90 from beneath the upper roof plate 9, sufficiently far to practically cover the recess 6 along the upper horizontal edge of the pan, so as to form a water proof pocket as 10, into which the upper edge of the screen 95 frame is adapted to project.

In the preferred construction of the invention a series of spring clips 11—11 are fixed to the upper horizontal edge of the screen plate, said springs being adapted to 100 press against the inner face of the vertical portion of the eaves molding so as to maintain the rear or inner face of the screen frame in contact with the relatively outer surface of the bottom of the surrounding 105 recess 6. A series of spring clips 12—12 are fixed in the lower horizontal portion of the recess 6, preferably by welding, in such

manner as to bear against the outer face of the lower edge portion of the screen frame. The vertical edge portions of the screen frame are turned outwardly as at 5 14—14 for strengthening the frame and presenting a straight even surface for contact with contiguous portions of the recess 6. With this construction the frame may be readily fixed in position by first introducing 10 its upper edge into the pocket 10 and then inserting its lower edge, behind the clips 12.

A series of raised portions 13—13 are formed along the lower edge of the frame to 15 provide suitable drains for the egress of the water which would otherwise accumulate behind the frame in the pan 2. These raised portions may be used as finger holds, for lifting the frame above the clips 12 when it 20 is desired to remove the frame for repairs, cleaning, or for other purposes.

It is not intended to restrict this invention to the specific details above described as numerous forms may be devised within 25 the scope of the claims forming part hereof, for instance, as illustrated in Fig. 4, the clips 11 may be disconnected from the screen frame and attached to a rigid part of the car structure as at 11^a in said figure; or, as 30 illustrated in Fig. 5, the clips 11^b may be formed of material sufficiently heavy as not to be within the term "spring," said clips simply forming pockets into which the edges of the screen frame fit snugly; or such pockets may be formed in any desired manner. The opposite vertical flanges as 14^a may be 35 extended and riveted or otherwise rigidly fixed to outstanding portions 5^a of the finishing plate, 5 by rivets which are accessible 40 and easily removable, such rivet connection being in addition to the clips formed along the horizontal edges or the pockets employed 45 in lieu thereof.

The metal frame inclosing the deck-win- 45 dow is formed at its inner portion with a vertical flange F, an outstanding flange H and vertical flange G, surrounding the deck- window-frame 1^a. The flange F rests in parallel continuity with the inturned or de- 50 pending flange i of the pan or hood 2, and the flanges F and i may be suitably connected. The inner deck lining may be secured to

these lapping flanges and the parts held in the positions shown in Figs. 2, 4 and 5.

The deck-pan flange i serves as a stop 55 during insertion of the metal frame for the deck-window, which frame is Z-shaped in section and which, as will be noted in Figs. 2 and 3, extends across the top of said deck- window and vertically downwardly at each 60 side thereof to the inclined ledge b' or window sill. This sill is flanged vertically upwardly at its inner end, as shown at s, and of itself would afford a stop against inward movement of the deck-window. However, a 65 raw edge of metal is objectionable, and to utilize the flange s, as well as to stiffen it and present a better finish, the lining 30 is bent inwardly, as at 31, thence upwardly, as shown at 32, parallel with the flange s, 70 and an inverted U-shaped cap 33 is fitted over the lapping flanges s and 32 and secured in position.

What we claim is:—

1. In a car structure a window pan having 75 an opening therein, the outer portion of the walls of said opening bent to form an outwardly facing recess outlining said opening, a removable screen frame disposed in said recess, and means attached to said pan, 80 retaining said frame in said recess.

2. In a car construction, the combination 85 with a deck-window pan, of a screen frame therefor and spring retaining means disposed between said pan and frame, said pan having a water table affixed thereto adapted to be engaged by said spring for retaining said frame, and adapted to prevent water dripping on said screen frame.

3. In a car construction, the combination 90 with a deck-window pan, of a screen-frame therefor and spring retaining means carried by said frame, said pan comprising a recess adapted for receiving said screen frame, and means adjacent said recess adapted to be engaged by said spring for retaining said frame. 95

In witness whereof we have hereunto set our hands in the presence of two witnesses.

LEVI CLIFTON SPARKS.

AUGUST WILLIAM LOUIS HARTBAUER.
